US00D950519S

(12) **United States Design Patent** (10) **Patent No.:** **US D950,519 S**
(45) **Date of Patent:** **** May 3, 2022**

(54) **EARPHONE**

(71) Applicant: **Dongguan Lanye Electronic Technology Co., Ltd**, Guangdong (CN)

(72) Inventor: **Rong Xie**, Guangdong (CN)

(73) Assignee: **Dongguan Lanye Electronic Technology Co., Ltd**, Guangdong (CN)

(**) Term: **15 Years**

(21) Appl. No.: **29/739,383**

(22) Filed: **Jun. 24, 2020**

(51) LOC (13) Cl. **14-01**

(52) U.S. Cl.

USPC **D14/206**; D14/226

(58) **Field of Classification Search**

USPC D14/206, 226, 188, 192, 372, 225; D29/112; 2/209, 423; 381/380, 381, 381/374; 345/7-9; 362/105, 86; 455/90.3, 575.1, 569.1

CPC H04R 25/00; H04R 25/02; H04R 1/1066; H04R 1/1016; H04R 5/033; H04R 5/0335; H04R 1/105; H04R 1/1058; H04R 19/04; H04R 11/04; H04R 1/1091; G02B 27/017; F21V 21/084

(57) **CLAIM**

The ornamental design for an earphone, as shown and described.

DESCRIPTION

FIG. 1 is a front and top perspective view of an earphone, showing my design.

FIG. 2 is a rear and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines adjacent the shaded areas and solid lines illustrate the bounds of the claimed design and form no part of the claimed design. All other broken lines are directed to portions of the headphone that form no part of the claimed design.

1 Claim, 8 Drawing Sheets
